UNITED STATES PATENT OFFICE.

WILLIAM TUTELMAN, OF PHILADELPHIA, PENNSYLVANIA.

ADJUSTABLE SLEEVE.

1,157,265.

Specification of Letters Patent. Patented Oct. 19, 1915.

Application filed September 8, 1913, Serial No. 788,504. Renewed March 15, 1915. Serial No. 14,514.

To all whom it may concern:

Be it known that I, WILLIAM TUTELMAN, a citizen of the United States, residing in Philadelphia, county of Philadelphia, State of Pennsylvania, have invented certain new and useful Improvements in Adjustable Sleeves, of which the following is a specification.

My invention relates to adjustable shirt sleeves, and it has for one object to provide means for adjusting a sleeve, particularly a shirt sleeve, which may be employed without disfiguring the appearance of the sleeve when in use in shortened condition.

10 A further object is to provide means whereby when the sleeve is not shortened a portion of the means employed for that purpose may be concealed from view.

My invention comprehends the construction and arrangement of parts as herein-after described, illustrated in the drawing and particularly pointed out in the claims. It should be understood, however, that changes in the details of construction may 25 be made within the scope of the claims without departing from my invention.

In the drawings, Figure 1 is a top plan view of the body part of a shirt and portions of a sleeve provided with my invention, a portion of the adjusting means being partially concealed; Fig. 2 is a front elevation of the top portion of the body part and one sleeve of a shirt provided with my invention and showing the adjusting means in use; Fig. 3 is an enlarged sectional view taken longitudinally of the upper portion of the sleeve and extending partially into the body of the shirt and showing in detail a construction embodying my invention. Fig. 4 is a view similar to that shown in Fig. 3, showing the adjusting means in use to shorten a sleeve; Fig. 5 is a view of strip ready to be attached to a sleeve; Fig. 6 is a section on the line 6—6 of Fig. 3; and Fig. 7 is a transverse section of the tab employed for connection with the shirt sleeve to shorten the same.

Referring to the drawings, 1 designates the body part of a shirt and 2 the sleeves of the same. In the manufacture of shirts the sleeves and body parts are first constructed after which the sleeves are sewn into place in the armholes provided in the body part for them. However, if the sleeves are to be provided with my invention, a strip of material 3, either the same or different in kind

from the material of the shirt, is placed in position inside the shirt sleeve at its inner end against the lower side of its upper part and is secured thereto by the button hole threads employed in working or binding the button holes 4 cut through the strip and the sleeve of the shirt as shown in Fig. 1. Near one end of the strip 3 it is slit or cut as shown at 6 and the side portions 7 are bent or folded over toward each other, as shown in Fig. 5, so that their edges are in proximate parallel relation to each other. The narrow tongue-like portion 8 thus formed is bent or folded over at its center, as shown at 10, its end terminating in substantial alinement with the slits or cuts 6. A button hole 11 is then cut and worked at a point near the folded end 10. The hole 11 is cut through the material of the tongue or tab 8 along a line in a plane at right angles to the plane of the said tongue or tab, the said plane being situated and extended between the adjacent edges of the folded-over side parts 7. The threads employed in making 20 the button hole 11 engage or catch the edges of the said folded-over edges and secure them to the central or body portion of the tongue or tab. It will be seen that in this way a tab may be very cheaply and conveniently constructed in which no raw edges are present. I have also provided a transversely extending slit or hole 14 through the sleeve and inner end of the strip 3.

The strip having been secured to the sleeve 30 by the threads of the button holes 4, and the button hole 11 and the hole or slit 14 having been finished, the tongue or tab is folded over the edge of the sleeve and the inner end of the latter is then placed in position in 40 the arm hole and secured therein in the usual manner by a double row of stitches 15. These stitches 15 pass through the overturned tongue or tab, as shown in Figs. 3 and 4, holding the same down and in position as shown.

I have shown the sleeve provided with four button holes 4, but the number of these holes may be changed as desired. It may be stated that these holes are for the reception of a button 16 adapted to be engaged in the button hole 11 in the tab. Other suitable means may be employed if desired for connecting the said tab to the sleeve to adjust its length.

When the tab is not in use for shortening the sleeve, it may be inserted through the

hole or slit 14, as shown in Figs 1 and 3, and thereby concealed. By thus providing means for concealing the tab when not in use, I obviate the objection of unsightliness and disfigurement of the appearance of the shirt.

In Figs. 2 and 4 I have illustrated the tab in use, showing the fold in the sleeve occasioned by its being shortened.

10 By my construction I have provided means for adjusting the length of the sleeves of a shirt, which means is so constructed as to cause practically no difference in the appearance of the shirt. Such means may be provided upon a shirt without adding materially to the usual cost of manufacture which is very important from a commercial standpoint.

I claim:

20 1. Sleeve adjusting means comprising a strip having its side portions adjacent to one end thereof folded over toward each other to bring their edges into proximity to each other and to form a relatively narrow portion, the said strip being secured to the inner side of a sleeve at its inner end portion by the threads of button holes formed in said sleeve and strip, and the said relatively narrow strip being folded upon itself 25 and provided with a button hole, and being then folded over the edge of the sleeve and secured in such folded over position by the threads by which the sleeve is secured in an arm-hole of a garment.

2. The combination of a shirt sleeve, a strip secured thereto upon its interior side at its inner end portion, said strip having a tongue-like portion folded over the edge of said sleeve and secured in such folded over position by the threads which secure the sleeve in the arm-hole of the shirt body, the said sleeve and strip having button holes extending longitudinally thereof, the threads of which secure said strip to said sleeve, and also having a transversely extending button hole situated adjacent to the edge of the sleeve for the reception of said tongue-like portion, substantially as described.

3. The combination of a shirt sleeve, a strip secured thereto upon its interior side at its inner end portion, said strip having a tongue-like portion folded over the edge of said sleeve and secured in such folded over position by the threads which secure the sleeve in the arm hole of the shirt body, and the said sleeve and strip having a transversely extending slit situated adjacent to the edge of the sleeve for the reception of said tongue-like portion.

In testimony that I claim the foregoing as my invention, I have hereunto signed my name this fifth day of September, A. D. 1913.

WILLIAM TUTELMAN.

In the presence of—

FLORENCE DEACON,
CARRIE E. KLEINFELDER.
